UNITED STATES PATENT OFFICE

2,030,387

HYDRAULIC PRESS

Louis A. Molin, Chicago, Ill.

Application September 25, 1933, Serial No. 690,862

12 Claims. (Cl. 100—50)

My invention relates to a hydraulic press and more particularly to a device of this character which is utilized for the extraction of oils and greases from oil-bearing seeds, animal tissues or cracklings, and other oil-bearing materials whose contents may be substantially removed by the application of pressure, with or without the addition of heat.

The press described and claimed in the present application is an improvement on that type of press in which there is employed a curb cylinder that is provided with a tamping or pre-pressing ring at one end and a principal ram at the opposite end, the tamping ring acting to fully charge the curb and the principal ram moving in a direction opposite to that of the tamping ring to effect the extracting operation, this arrangement resulting in certain economies in the overall length of the press owing to the necessity for moving the principal ram only a short distance. The ram is also provided with an extension that encloses a steam coil that applies heat to the material being compressed substantially throughout the length of the curb in order to maintain the charge in the curb at a temperature that will facilitate the extraction of the oil therefrom.

It is one of the objects of the present invention to further improve the efficiency of the indicated press and to further reduce the distance through which it is required to move the principal ram by holding the freely slideable curb in the position to which it has been shifted during the compressing of the material by the ram and to thereafter return the ram to original position which provides with the then-shifted curb an opening through which the residue cake may be discharged by the continued movement of the tamping member.

A further object is to provide a hydraulic press of the character indicated in which an oil seal ring is interposed between the ram and the oil pan and maintained in contact with the oil pan during the shifting movement of the curb in order to prevent any seepage of the extracted oil along the wall of the ram piston, this oil seal ring being engaged by the ram during its re-tracting movement to provide the discharge opening above referred to, and the curb re-engaging the sealing ring after the residue cake has been completely evacuated.

These and further objects of my invention will be set forth in the following specification, reference being had to the accompanying drawings, and the novel means by which said objects are effectuated will be definitely pointed out in the claims.

In the drawings:—

Figure 1 is an elevation, partly in section, of my improved press, the several parts being shown in curb-charging position.

Fig. 2 is a plan view of the press, as viewed in the direction of the arrow 2 in Fig. 1, showing the upper header of the press and the location of the hydraulic cylinders forming part of the mechanism for actuating the tamping ring and for holding the curb in its raised position.

Fig. 3 is a view of the lower portion of the press as viewed in the direction of the arrow 3 in Fig. 1 showing the laterally directed chutes onto which the residue cake is discharged.

Figs. 4 and 5 are elevations, partly in section, corresponding to the view shown in Fig. 1, illustrating the ram in the act of compressing the material in the curb and the tamping ring discharging the residue cake through the opening 15 between the curb and ram, respectively.

The specific embodiment of my invention, as set forth in the present application, relates to a press for the extraction of greases from animal casings or cracklings, but it will be understood that the broader phases thereof are likewise applicable to the general extraction of fluid from any material that may be subjected to pressure for this purpose.

Referring to Fig. 1 of the drawings, the numeral 10 designates a suitable foundation which is provided with a pocket 11. The sides of this pocket are recessed to receive a pair of girders 12 upon each of which rests a pair of nuts 13 that are mounted upon the lower ends of a pair of tie rods 14 that extend upwardly through the adjacent end of a lower header 15. In plan view, the header 15 possesses the generally rectangular formation shown in Fig. 2 and a tie rod 14 is located adjacent each corner thereof. The rod 14 projects upwardly through an upper header 16 which possesses a marginal outline similar to that of the lower header and on the upper ends of the rods 14 are mounted nuts 17 similar to the nuts 13. The lower and upper headers are maintained in abutting relation to their associated nuts 13 and 17 by means of clamping collars 18. The headers and tie rods constitute a box-like structure which forms the principal framing of the press and the entire weight of which is carried on the girders 12.

An hydraulic cylinder 19 is preferably integral- 55 ly formed with the header 15 and extends downwardly in the pocket 11. A piston 20 is reciprocably mounted in the cylinder 19 and actuating fluid, such as oil or the like, may be introduced into the cylinder by means of a pipe 21 that is in communication with a remote pumping mechanism.

An annular shell 22 projects upwardly above the head 23 of the piston and has seated on the upper end thereof a ram 24. A sleeve-like portion 25 extends from the under side of the ram and is guidably received within the interior of the shell 22 so that when fluid is introduced into the

60

cylinder 19, the piston 20 and the ram 24 move as a unit. A hollow stem 26 projects upwardly from the ram 24 in axial alignment with the cylinder 19 and encloses a steam coil 27 into which steam or other suitable heating medium is delivered and exhausted from by means of pipes 28 and 29, respectively, which extend upwardly through a frusto-conical cover 30 mounted on the upper end of the stem 26. The steam pipes 28 and 29 also pass upwardly through a supply pipe for the oil-bearing material as hereinafter described.

The squeezing surface 31 of the ram is preferably inclined outwardly from the stem 26, as shown in Fig. 1, and a pair of knife-like formations 32 are located on this surface on opposite sides of the steam chamber. As many of these formations may be employed as the conditions of operation require and they are intended to cooperate with a tamping ring, presently described, for breaking up the residue cake into smaller fragments during the discharging operation.

The ram 24 normally closes the lower end of a curb 33 which comprises a plurality of axially spaced rings 34 that are internally connected by means of longitudinally-extending bars 35. As shown clearly in Fig. 1, the bars are arranged in the manner of barrel staves, but are spaced circumferentially from each other sufficient to provide openings 36 which are large enough to permit of the easy flow of oils or greases therethrough, while substantially restricting the outward movement of solid material when under pressure. Secured to the lower ends of the bars 35 is an oil pan 37 whose inner face 38 is tapered upwardly for a purpose presently explained, but which is substantially a continuation of the inner faces of the curb bars 35. Oils or greases which may collect in the oil pan 37 are evacuated through a flexible hose 39 and in order to maintain the oil in this pan above the congealing point and so facilitate its handling, the pan embodies an internal annular passage 40 which, on one side of the press is in communication with a flexible, steam inlet hose 41 and on the opposite side with a corresponding exhaust hose 42.

The tapered face 38 of the oil pan engages with a correspondingly shaped face on an oil-sealing ring 43 whose inner face is in sliding engagement with the annular projection 22 on the piston 20. These opposite faces of the sealing ring may be provided with suitable packing in order to prevent any leakage of the extracted oil between the ring and pan and between the ring and piston 20. In the position of the parts as shown in Fig. 1, the upper side of the ring is in engagement with a shoulder 44 which is provided on the ram, while the lower side of the ring is engaged by a plurality of coil springs 45 whose lower ends are mounted in suitable pockets 46 provided on the lower header 15. The extending action of these springs maintains sealing contact between the ring 43 and pan 37 not only in the position shown in Fig. 1, but also in the shifted position of the curb during the principal compressing step of the operation.

In order to provide for the free movement of the curb along the rods 14 during the principal squeezing operation, arcuate shoes 47 are attached to the upper curb rings 34 and to the oil pan. The curb is free to move upwardly from the position shown in Fig. 1, but movement downwardly is restricted by a plurality of clamping collars 48, one for each of the rods 14.

A supply tube 49 is slidably mounted in the upper header 16 in axial alignment with the cylinder 19 and through this tube is delivered the oil bearing material to the annular compression chamber 50 located between the curb and stem 26. The lower end of the tube 49 projects below the upper header and has attached thereto a tamping ring 51 whose dimensions are such that it fits closely in the curb chamber 50.

The tamping ring is hydraulically actuated by means of a plurality of piston rods 52 which project upwardly through the header 16 into cylinders 53 mounted on the upper side of the header. A piston 54 is attached on the upper extremity of each piston rod 52 and this piston is of the double acting variety. Actuating fluid is introduced into the cylinders above the pistons 54 by pipes 55 to thereby move the tamping ring downwardly from the position shown in Fig. 1, while a reverse movement of the ring is effected by the delivery of fluid into the cylinders below the pistons through pipes 56, it being understood that the pipes 55 and 56 are in communication with a suitable pump mechanism.

A pair of cylinders 57 is also provided on the upper header on opposite sides of the vertical axis of the press and within each of these cylinders operates a piston 58 having a piston rod 59 whose lower end is provided with an arm 60 that engages with the under side of an upper curb ring 34. At an appropriate time in the operation of the press, as hereinafter explained, actuating fluid is introduced into the cylinders 57 below the pistons 58 through pipes 61 to hold the curb in its raised position.

A pair of oppositely extending chutes 62 are carried by the lower header 15 and are so disposed with reference to the lower end of the compression chamber 50 that, when the ram 24 is moved downwardly upon the completion of the pressing operation to provide a discharge opening for the residue, the latter will fall directly on the chute on opposite sides of the press for subsequent transfer to containers, belt conveyors, or the like.

In the operation of the press, it will be understood that, when the several parts of the press are occupying the relative positions shown in Fig. 1, the press is in condition to be charged, since the ram is closing the lower end of the curb, while the tamping ring is sufficiently elevated to provide communication between the interior of the curb and the supply tube 49 through which the oil-bearing material passes by gravity. The material is permitted to flow into the curb until the curb has become loosely packed, whereupon the tamping ring is moved downwardly to more completely pack the initial charge, which movement may also effect some degree of compression that may be sufficient to extract some oil from the material. The ram may be maintained in the position shown in Fig. 1, either by an appropriate pressure established in the cylinder 19, or by actually abutting against the bottom of this cylinder, so that the ram serves as an abutment against the pressing action of the tamping ring. The tamping ring is thereupon retracted to permit an additional accumulation of loosely packed material in the curb, followed by another tamping operation to compress this portion of the charge, and these steps may be repeated as often as is desirable until the curb has been completely charged with pre-pressed, oil-bearing material. During this entire operation, as well as during all subsequent operations of the press, steam or some

other heating medium is continually passing through the heating coil 27 so that the oil in its passage outwardly between the curb bars is never given an opportunity to congeal. Steam is also 5 constantly passing through the steam space in the oil pan, so that grease which is collected therein is always maintained in a fluid condition.

Upon the completion of the final tamping operation, that is, after the curb has acquired its maximum charge, the downwardly-acting, hydraulic pressure on the tamping ring is relieved and fluid under pressure is introduced into the cylinder 19 to thereby cause an actuation of the 10 ram 24 upwardly. The outer curb, owing to its substantially floating mounting on the tie rods 14, moves upwardly with the ram during the initial phases of the latter's movement and this upward movement of the ram also causes an upward movement of the tamping ring until the latter abuts against the under side of the upper header 16 which thereafter resists the pressure created by the ram, so that the upper thrust of the ram is taken substantially by the principal 15 frame of the machine. The extracted oils and greases flow radially of the curb for discharge through the openings between the curb bars and subsequent collection in the oil tank, the steam in the chamber 50 maintaining the charge in the 20 curb at the most satisfactory extracting temperature.

The final act of compression is more particularly illustrated in Fig. 4 and it will be particularly noted that the ram has become separated 35 from the sealing ring 43, but that the latter not only maintains sealing contact with the annular extension on the piston 20, but also with the tapered, inner face of the oil pan by reason of the extending action of the springs 45. Any seepage 40 of the oil between the ring and piston extension and between the ring and oil pan is therefore positively prevented and such oil as may collect on the top surface of the ring flows outwardly into the oil pan.

Upon the completion of the main pressing operation, fluid is introduced into the cylinders 57 below the pistons 58 for the purpose of temporarily restraining any tendency of the curb to move downwardly. At the same time, pressure in 45 the cylinder 19 is relieved and fluid under pressure is introduced into the cylinders 53 above the pistons 54 in order to move the tamping ring downwardly. This downward movement of the tamping ring acts through the residue cake to move the ram and the sealing ring engaged thereby downwardly until the ram reaches its lowermost position as indicated in Fig. 1. Since the outer curb is maintained in the raised position shown in Figs. 4 and 5, this downward shift of 50 the ram creates an annular discharge opening 63, as clearly shown in Fig. 5, between the oil pan and the ram through which the residue cake is discharged onto the chutes 62 by the continuing movement of the tamping ring and, during this 55 action, this cake is split by the knife blocks 32.

After the discharging action is completed, the tamping ring is retracted upwardly by hydraulic pressure and the pressure in the cylinders 57 is relieved to permit a dropping of the curb to the 60 position shown in Fig. 1 by gravity, whereupon the fresh material in the supply pipe is again free to move downwardly into the curb chamber for subsequent treatment by the tamping ring.

A press of the foregoing character possesses 65 several important operating advantages from the

standpoint of efficiently handling the oil or grease-bearing materials. In the first place, the press is loaded and unloaded automatically, without any necessity for manual labor of any character, other than an operator to control the admission 5 of pressure to the several hydraulic cylinders. The tamping or pre-pressing movements of the tamping ring insure that the curb will be loaded to its maximum capacity for each cycle of operation, so that the press operates at maximum 10 efficiency at all times, regardless of the native, loose nature of the material. By holding the curb in its uppermost position to provide a discharge opening, it is possible to restrict the principal ram to relatively short movements, thus 15 securing certain economies in the operation of the pumping mechanism which supplies fluid to the cylinder 19. Moreover, the oil seal ring provides a very effective method of preventing any leakage along the annular extension on the piston 20 and the construction is such that it does not interfere with the downward movement of the ram to provide the discharge opening indicated above.

I claim:

1. An hydraulic press comprising in combination, a freely slideable curb, a ram movable to compress the material in the curb and retractable to its initial position, the curb moving with the ram during the initial stage of compression and the ram thereafter moving relative to the curb until 25 compression is complete and the ram in its retracted position defining an opening with the adjacent end of the shifted curb, means for holding the curb in its shifted position, and positively 30 actuated means for discharging the residue cake 35 through the opening.

2. An hydraulic press comprising in combination, a freely slideable curb, a ram normally closing one end of said curb, said ram being movable 40 to compress the material in the curb and retractable to its initial position and the curb moving with the ram during the initial stage of compression and the ram thereafter moving relative to the curb until compression is complete, means 45 for holding the curb in its shifted position to thereby define an opening with the ram when the latter is retracted to its initial position, and positively actuated means for discharging the residue cake through the opening.

3. An hydraulic press comprising in combination, a freely slideable curb, a ram normally closing one end of the curb and movable to compress the material in the curb, the curb moving with the ram during the initial stage of compression 50 and the ram thereafter moving relative to the curb until compression is complete, means for holding the curb in its shifted position, and means 55 for returning the ram to its initial position while the curb is being held in its shifted position to thereby create an opening between the shifted curb and ram, said last named means also discharging the residue cake through the opening.

4. An hydraulic press comprising in combination, a freely slideable curb, a tamping member 60 and a ram located adjacent the opposite ends of the curb, respectively, means for actuating the member and ram in opposite directions at different times to fully charge and compress the material in the curb, respectively, the curb moving 65 with the ram during the initial stage of compression and the ram thereafter moving relative to the curb until compression is complete, means for holding the curb in its shifted position, and means for actuating the tamping member to 70 75

- thereby form an opening between the curb and ram through which the residue cake is discharged by the continued movement of the tamping member.
5. An hydraulic press of the vertical type comprising in combination, curb guides, a curb freely slideable along the guides, a ram movable to compress the material in the curb and retractile to its initial position, the curb moving with the ram during the initial stage of compression and the ram thereafter moving relative to the curb until compression is complete and the ram in its retracted position defining an opening with the adjacent end of the shifted curb, means for holding the curb in its shifted position, and means for discharging the residue cake through the opening, said curb returning by gravity to its initial position when the holding means is released.
6. An hydraulic press comprising in combination, upper and lower headers, curb guides connecting the headers, a curb freely slideable on the guides, a tamping member and a ram located adjacent the opposite ends of the curb, respectively, means for actuating the member and ram in opposite directions at different times to fully charge and compress the material in the curb, respectively, the curb moving with the ram during the initial stage of compression and the ram thereafter moving relative to the curb until compression is complete, means for holding the curb in its shifted position, and means for moving the tamping member to thereby return the ram to a position defining an opening with the shifted curb through which the residue cake is discharged by the continued movement of the tamping member.
7. An hydraulic press comprising in combination, a slideable curb, a collecting pan carried by the curb, a ram movable to compress the material in the curb and retractile to its initial position, the curb moving with the ram during compression, a sealing ring having sealing contact with the curb and ram and adapted to direct the expressed fluid into the pan, means for holding the curb in its shifted position, the ram moving the ring during its retracting movement to provide a discharge opening with the adjacent end of the shifted curb, and means for discharging the residue cake through the opening.
8. An hydraulic press comprising in combination, a slideable curb, a collecting pan carried by the curb, a ram movable to compress the material in the curb and retractile to its initial position, the curb moving with the ram during compression, a sealing ring having sealing contact with the curb and ram and adapted to direct the expressed fluid into the pan, means for maintaining contact of the ring with the curb during its shifting movement, means for holding the curb in its shifted position, the ram moving the ring during its retracting movement to provide a discharge opening with the adjacent end of the shifted curb, and means for discharging the residue cake through the opening.
9. An hydraulic press comprising in combination, a slideable curb, a collecting pan carried by the curb, a ram movable to compress the material in the curb and retractile to its initial position, the curb moving with the ram during compression, a sealing ring having sealing contact with the curb and ram and adapted to direct the expressed fluid into the pan, means for holding the curb in its shifted position upon the completion of compression, the ram moving the ring during its retracting movement to provide a discharge opening with the adjacent end of the shifted curb, and means for discharging the residue cake through the opening, said curb returning by gravity to its initial position in contact with the sealing ring when the holding means is released.

10. An hydraulic press comprising in combination, a slideable curb, a collecting pan carried by the curb, a ram normally closing one end of the curb, said ram being movable to compress the material in the curb and retractile to its initial position and the curb moving with the ram during compression, a sealing ring adapted to direct the expressed fluid to the pan and having sealing contact with the curb and ram and adapted to be engaged by the ram during the latter's retracting movement, means for holding the curb in shifted position upon the completion of compression, the retracting movement of the ram shifting the sealing ring from contact with the pan to thereby provide an opening with the adjacent end of the curb, and means for discharging the residue cake through the opening.

11. An hydraulic press comprising in combination, a slideable curb, a collecting pan carried by the curb, a tamping member and a ram located adjacent the opposite ends of the curb, respectively, means for actuating the member and ram in opposite directions at different times to fully charge and compress the material in the curb, respectively, the curb moving with the ram during compression, a sealing ring having sealing contact with the curb and ram and adapted to direct the expressed fluid into the pan, the ring being adapted to be engaged by the ram during the latter's retracting movement, means for holding the curb in its shifted position upon the completion of compression, and means for actuating the tamping member to thereby move the ram and sealing ring to a position providing a discharge opening with the curb through which the residue cake is discharged by the continued movement of the tamping member.

12. An hydraulic press of the vertical type comprising in combination, curb guides, a curb freely slideable along the guides, a ram movable to compress the material in the curb and retractile to its normal position, the curb moving with the ram during compression, a collecting pan surrounding the lower end of the curb and attached thereto, a sealing ring having sealing contact with the curb and ram and engaged by the latter, the ring being adapted to direct the expressed fluid into the pan, means for holding the curb in its shifted position upon the completion of compression, the ram moving the ring during its retracting movement to provide a discharge opening with the adjacent end of the shifted curb, and means for discharging the residue cake through the opening, said curb returning by gravity to its initial position in contact with the sealing ring when the holding means is released.

LOUIS A. MOLIN.
